UNITED STATES PATENT OFFICE

95,847

DESIGN FOR A TANK VEHICLE BODY

Joseph M. Kramer, Kansas City, Mo., assignor
to Andrew A. Kramer, Kansas City, Mo.

Application October 29, 1934, Serial No. 53,810

Term of patent 14 years

To all whom it may concern:

Be it known that I, Joseph M. Kramer, a citizen of the United States, residing at Kansas City, in the county of Jackson and State of Missouri, have invented a new, original, and ornamental Design for a Tank Vehicle Body, of which the following is a specification, reference being had to the accompanying drawing, forming a part thereof.

Fig. 1 is a view in side elevation of a tank vehicle body showing my new design,

Fig. 2 is a plan view of said body, and
Fig. 3 is a rear elevation thereof.

I claim:

The ornamental design for a tank vehicle body substantially as shown.

In testimony whereof I hereunto subscribe my name this 19th day of October, 1934.

JOSEPH M. KRAMER.
